UNITED STATES PATENT OFFICE.

PATRICK J. DALTON, OF NEW YORK, N. Y.

SIGN.

SPECIFICATION forming part of Letters Patent No. 355,510, dated January 4, 1887.

Application filed February 9, 1886. Serial No. 191,360. (No model.)

To all whom it may concern:

Be it known that I, PATRICK J. DALTON, of the city, county, and State of New York, have invented a new and Improved Sign, of which the following is a full, clear, and exact description.

My invention relates more particularly to sheet-metal signs; and the object of the invention is to provide a sign of this character which will be protected from the influences of the weather, which not only discolor the sign surface but cause the lettering to lose its luster.

The invention consists of the special construction of the sign, as hereinafter described and claimed.

Reference is to be had to the accompanying drawings, forming a part of this specification, in which similar letters of reference indicate corresponding parts in both the figures.

Figure 1 is a front elevation of a sign made in accordance with my invention, and Fig. 2 is a sectional elevation of the same taken on the line $x x$ of Fig. 1.

The frame A of the sign is by preference made of wood, and may be of any suitable size. At the front the frame A is by preference slightly recessed, as shown at a , to receive the sign B, which in this instance is a polished metal plate with the sign-letters b enameled, embossed, painted, or otherwise placed or formed upon it. Around the edges of the sign B are placed the narrow strips c, and over the sign and resting upon these strips is placed the glass plate C, which is

held in place by the screws d which pass through the glass and the sign B and screw into the frame A, the strips e serving to prevent the plate from coming in contact with the sign.

The glass C is hermetically sealed in or to the frame A over the sign B by the layers or strips e, of plaster-of-paris or other material, so that external air cannot reach the lettered surface of the sign. In this manner all discoloration of the sign is prevented, thereby saving the time and labor of cleaning, and the influences of the weather cannot loosen or dim the luster of the lettering nor the polish of the sign, and the reflecting-surface of the glass front does not diminish, but rather adds to the brightness and beauty of the sign.

Having thus fully described my invention, I claim as new and desire to secure by Letters Patent—

A sign comprising the frame A, having a recess, a , into which the metal sign-plate B fits flush with the surface of the frame, strips e around the sign-plate near its outer edges, the glass plate C, resting on the strips, screws d, passing through the glass and the sign-plate into the frame, and the sealing material e, filling in the space around the glass and strips between their outer edges and the outer face of the frame beyond the recess, substantially as set forth.

PATRICK J. DALTON.
